TELEGRAPH SYSTEM

Robert Helmert, Berlin-Lankwitz, Germany, assignor to C. Lorenz Aktiengesellschaft, Berlin-Tempelhof, Germany, a company

Application April 23, 1937, Serial No. 138,538
In Germany April 23, 1936

6 Claims. (Cl. 178—2)

The present invention relates to telegraph systems in which interconnections are built up over selectors which are adapted to be set by impulses similar to those used for the telegraph signals.

5 It may occur in such systems that undesired connections are established in cases when telegraph signals are caused to influence the selector magnet due to interferences or irregular manipulations by the operators, whereby the selector is brought into an undesired position.

In order to avoid this disadvantage, the present invention provides switching means which, in case that an anomalous train of impulses reaches a selector, prevent its testing into a line. In 15 such event a further feature of the invention comprises the release of all selectors previously set and also the disconnection of the telegraph apparatus allotted to the subscriber's station.

An anomalous train of impulses exists either 20 when the number of pulses applied to the selector exceeds the maximum number of steps provided for its setting, or, in cases that hunting selectors are concerned, when subsequent to a finished train of impulses additional impulses arrive before the selector has tested. An excessive number of impulses may occur due to operation of the transmitting key during the period of selective dialing. The other type of anomalous impulse train may be explained more fully by 25 briefly considering the operation of an impulse operated switch. In this type of switch a train of impulses serves to position a selector member, after which a pause of predetermined duration is necessary for the selector to test and complete 30 the connection. Other series or trains of impulses then serve to make further connections as is well known in the art. If, then, a second train of impulses arrives before the selector has tested, the effect will be similar to an extension 35 or an addition to the original impulse train and therefore will not give the desired indication.

The present invention will be more readily understood from the following description taken in conjunction with the accompanying drawings, 40 in which:

Fig. 1 shows a wiring diagram of a subscriber's station equipped with a printing telegraph apparatus; Fig. 2 shows the wiring diagram of a preselecting device; while Fig. 3 represents the 45 circuit arrangement of a group selector equipment.

The relays are designated with capital letters and their pertaining contacts carry the corresponding designations in small letters which are 50 primed when distinction therebetween is re-

quired. The contacts k_0 , k_1 and k_2 shown in Fig. 3 are closed in dependence upon vertical selector movements, the contact k_0 , however, is not closed before the 10th step. The contacts w_1 to w_4 are closed on a rotary motion of the selector. The contacts w_{11} are closed by the selector on its 11th step which effects the release.

The printing telegraph apparatus according to Fig. 1 and the preselector device according to Fig. 2 are interconnected over the two lines a' and b' , while the last mentioned preselector device is connected to the group selector arrangement according to Fig. 3 over the lines a'' , b'' and c'' . When the system is in a condition of rest, all contacts are in a position as illustrated in the Figs. 1, 2 and 3. Only one single subscriber's station has been illustrated in the present embodiment of the invention. The corresponding station is designed in exactly the same manner as the station shown in Fig. 1, while its allotted preselector and group selector arrangements correspond to those shown in the Figs. 2 and 3. The outgoing lines a'' , b'' and c'' shown at the right side of Fig. 3 lead to the final selectors (not shown) which operate in a manner well known in connection with automatic telephony, from where they are extended to the lines of the co-operating station which correspond to the line a_{10} , b_{10} and c_{10} of Fig. 2.

When for the purpose of communication a connection is to be established from the printing telegraph apparatus in Fig. 1 to a corresponding station, the operator of the calling station actuates the calling key AT of his station, whereby the left winding of relay E is energized in a circuit which is traced from the battery B through the left winding of relay E, contact n_1 , line b' , relay P' and its shunted resistance W_1' , receiving magnet EM, calling key AT, impulse contact n_{11} of the dialling disc, line a' , contact n_2 to the battery B. The right winding of relay E is continuously supplied, but the current now flowing through the left winding thereof is of twice the intensity and acts in opposing sense, so that this relay operates its contact e to the upper position. The operation of contact e removes the short circuit for the relay R which now attracts, thereby closing its contacts r_1 and r_2 . The rotary magnet D is then started in an energizing circuit which is established by the contact r_1 over the contacts t_4 , h_2 , rotary magnet D of the preselector, interrupter U, battery to ground, so that the preselector starts its movement, whereby its wiper assemblies a , b , c and d test for a free group of lines a'' , b'' , c'' . As soon 55

as the wipers have found a free group of lines, the relay T having windings T₁, T₂ and T₃ is operated in a circuit established from ground over the contacts r₂, h₂, windings T₁, T₂ of relay 5 T, wiper e, line c'' of the free group of lines, contact k₁ (Fig. 3), contacts y₁, y₂, relay C, battery to ground. The relay T has one highly resistive winding T₁ which permits this relay to attract only in cases when no further preselector is connected with the c-wire which is to be tested, i. e. when no potential drop exists across the relay C of the group selector. Relay C is provided with two windings C₁ and C₂.

The relay T reverses its contacts t₁, t₂, t₃ 10 and t₄. The highly resistive winding T₁ of the relay T is short circuited at the contact t₃, so that a current of higher intensity now flows over the c-wire. As a result thereof an increased potential drop prevails at the C-relay of the appertaining group selector, whereby further preselectors are prevented from testing into this group selector, which is simultaneously characterized as busy. The reversed contact t₄ interrupts the circuit for the rotary magnet D of the preselector 15 which is arrested in the position to which it has been set. The contact t₄ also establishes a circuit for the relay H from ground over the wiper d, contacts h₁, t₄, relay H, battery to ground. The energizing circuit for the relay H 20 is sustained over the contacts h₁ and r₁ to ground as soon as this relay has attracted. The contact h₃ disconnects the left winding of the relay T, but this is at first without any effect as the winding T₂ of the relay T remains energized 25 over the contacts r₂ and t₃. The circuit for the rotary magnet D which already has been interrupted by the reversed contact t₄ is broken again at the operated contact h₂.

The reversed contact t₂ connects the relay S 30 with the battery in a circuit which is traced from ground, relay S, contact t₂, wiper b, line b'', contact p₂ (Fig. 3), and contact y₄, battery to ground. Due to the fact that this battery applies a voltage to the relay S of opposite sense than 35 that supplied thereto over the back contact t₂ of relay T, the relay S reverses its contact s. The relay N is also influenced over the same circuit as the current flow through its right winding has been reversed. The two windings of this 40 relay N are so dimensioned that the effect of the right winding predominates over that of the left winding. The contacts s, n₁ and n₂ now reversed accomplish current reversal over the subscriber's loop which is supplied from the battery B and shown in Fig. 1. This reversed current flow operates relay P' which closes its contact p' thus connecting the relay M to the main supply Ne. On its energization the relay M closes 45 its contacts m₂, m₃ and m₄ and opens its contact m₁. The contacts m₂ and m₄ connect the motor Mo of the printing telegraph apparatus to the main supply Ne with the result that the apparatus is started. The contact m₁ removes the short circuit from the transmitter contact SK. The 50 contact m₂ together with the release key ST provides a shunt connection across the condenser C and the resistance Wi, so that the direct current of the subscriber's loop now flows over the transmitter contact SK and through the receiving magnet EM.

At first only the two winding relay C of the group selector (Fig. 3) is operated, whereby its contacts c₁, c₂ and c₃ are reversed. The setting of the group selector during the dialling operation 55 at the subscriber's station is effected in a well

known manner. As soon as the subscriber (Fig. 1) actuates his dial, the contact n₁ is opened and closed in a rhythm which corresponds to the pulses sent out by the dial. For the purpose of protecting the printing telegraph receiver against interferences, the receiving magnet EM is simultaneously short circuited by the agency of the contact n₂. The current interruptions in the subscriber's loop cause the relay E to operate, due to the fact that the current through the left winding of this relay decays at each interruption of the subscriber's loop a', b', so that the current which continuously flows through the right winding of this relay again reverses the contact e. The movement of the contact e operates the two winding impulse relay I of the group selector (Fig. 3) over the line a'', contacts y₅, k₀, w₁, relay winding I₁ and battery to ground, because the oscillating contact e intermittently applies battery potential in series with the battery potential at relay I or a battery potential which opposes the battery potential at the relay I.

The contact i₂ which is closed in rhythm with the pulses, when the impulse relay I is active, establishes a circuit for the magnet for vertical movement H₂. This current flows over the following path: ground, supervisory relay WK, contacts c₂, w₂, i₂, vertical movement magnet H₂, battery, ground. The three winding relay P is 25 operated at the same time as the relay H₂ over winding P₁ connected in parallel therewith. Since this relay is equipped with a timing device it is not permitted to release as long as the successive pulses of an impulse train arrive. This 30 relay P releases after the first train of impulses has been finished, and the succeeding incoming train of impulses energizes the rotary magnet D' from ground over the relay WK, contacts p₄ 35 i₁, k₂, rotary magnet D' and battery to ground, so that the group selector will be set to an idle connector (not shown) of the desired group. The further connection to the subscriber's station is not illustrated since it is not a part of this invention and is well known to those skilled 40 in the art.

If the teleprinter apparatus of the subscriber's station instead of impulse trains corresponding to the rules of operation transmits an anomalous train of impulses, e. g. telegraph signals by an 45 opening or closing of the transmitter contact SK, the impulse relay I (Fig. 3) is first caused to operate in the same manner as above described in connection with the transmission of dialling impulses. This relay in turn actuates the vertical motion magnet H in the energizing circuit above explained. Since the relay P remains attracted during the arrival of the successive pulses as previously stated, the contacts p₁, p₂ and p₃ remain closed and the contact p₄ remains open 50 during this interval. As soon as the group selector has finished its 10th vertical step, the cam contact k₀ is reversed. At the conclusion of the pulse which effected this 10th step, even the contact i₄ opens, so that the energizing circuit 55 for the relay I is interrupted, but at the same time a new circuit is established for three winding, slow release relay Y over the contacts y₅, k₀, i₃, relay winding Y₁, battery to ground. The succeeding pulse therefore causes the relay Y to 60 attract, which opens its contact y₃, thus interrupting the testing circuit for the relay P at winding P₂ with the result that the selector is prevented from testing a line. Upon operation 65 relay Y locks itself over winding Y₂ by opening 70 75

contact y_2 . Since the relay winding I_1 is not again energized, the slow to release relay P releases, closing contact n_4 , whereupon the selector turns due to the energization of its rotary magnet D' in a circuit which is traced from ground through relay WK , over contacts p_4 , i_1 , k_2 , rotary magnet D' , battery to ground. The attraction of the rotary magnet D' causes its contact d' to close, so as to establish a circuit for winding I_2 of the relay I . This relay attracts and opens its contact i_1 , thereby recurrently interrupting the circuit for the rotary magnet D' . The above described operation of this magnet advances the selector step by step, but the selector is unable to test for a free line since, as mentioned above, the circuit for the test windings P_2 of relay P is interrupted at the contact y_2 . Rotary switch D' opens contacts w_1 , w_2 , w_3 and w_4 as soon as it operates, but does not operate w_{11} and w_{12} unless it makes 11 steps.

The polarity of the current source which is connected to the wire b'' over the contact p_2 is reversed by the reversed contact y_4 with the result that the relays S and N (Fig. 2) return their contacts into the positions illustrated in the drawings. The direction of current flow through the subscriber's line a' , b' is reversed as the result of the returned contacts s , n_1 and n_2 , so that the relay P' (Fig. 1) again opens its contact p' thus interrupting the current path for the relay M . The so returned contacts m_3 and m_4 open the circuit for the motor M_0 of the printing apparatus which is stopped, while the contact m_2 simultaneously interrupts the subscriber's line. The relay E (Fig. 2) thereby returns its contact e into the position shown and short-circuits the relay R which releases after the elapse of a given period. The opened contact r_1 effects the release of the relay H since the contact n_3 has already been opened. The release of the relay T and the release of the relay C of the group selector is accomplished, when the contact r_2 is restored to normal. Also the relay Y of the group selector releases owing to the interrupted loop in consequence of the returned contacts t_1 and t_2 . This relay is thereby restored to the condition of rest. The selector is homed in a manner well known in the technics. The entire system is now restored to a condition of rest before an undesired connection is built up as the result of telegraph signals from the printing telegraph apparatus influencing the selector. The stopped printing telegraph apparatus indicates to the subscriber that a regular connection has not been established. The subscriber may now establish a correct connection by the agency of his dial.

If an anomalous train of impulses follows after

the proper operation of the vertical selector H_2 the rotary selector D' operates in a similar manner to that described above except that it causes the rotation at a different level corresponding to that selected instead of on the tenth level as described above. Upon its eleventh step rotary switch D' closes contact w_{11} impressing reverse current on line b'' and causing release of the apparatus as described above. Closing of contact w_{12} serves to impress reverse polarity on line c'' and effect release of other mechanism.

What is claimed is:

1. A telegraph system comprising telegraph sets, lines and selectors for interconnecting said sets, means for impressing a normal series of current impulses on one of said lines for operating said selectors for testing to select an idle line for establishing a circuit between said sets for inter-communication, and switching means responsive to an anomalous series of current impulses im- 15 pressed on said line for disabling said selectors from testing.

2. A telegraph system according to claim 1, further comprising means controlled by said switching means for causing release of said tele- 25 graph sets from said connection.

3. A telegraph system according to claim 1, in which said switching means comprises a relay operated in response to a series of current impulses exceeding normal. 30

4. A telegraph system according to claim 1, in which said switching means comprises a relay, means responsive to the highest normal step of one of said selectors for preparing an operating circuit for said relay, and means for closing the 35 circuit of said relay in response to an additional current impulse.

5. A telegraph system comprising telegraph sets, lines and selectors for interconnecting said sets, said selectors being operated in steps for 40 making suitable selections, means for successively impressing a series of impulses below a pre-determined maximum number on said lines for operating said selectors for establishing a circuit between said sets for communication pur- 45 poses, and means responsive to a series of current impulses above said maximum number for disabling said selectors from completing a connection.

6. A telegraph system according to claim 5, in 50 which said selectors operate by testing for establishing said circuit, and in which said disabling means comprises a relay operated in response to advance of said selectors beyond a predetermined maximum position for opening said testing cir- 55
